1,925,229

CONCRETE FLOOR CONSTRUCTION AND
MOLD THEREFORJacob Brunle, Brooklyn, and Andrew Weggen-
man, Scarsdale, N. Y.

Application July 18, 1931. Serial No. 551,610

3 Claims. (Cl. 72—66)

The invention relates to an incombustible reinforced concrete floor structure and to a novel hollow mold member for use therein and adapted to become an integral part of the finished floor.

5 The invention has for an object the provision of a hollow metal lath or expanded metal mold over which is poured the concrete to form a slab, and also between adjacent molds to form the joists, said hollow mold as well having an integral portion providing a ceiling element.

A still further object of the invention resides in the provision of means whereby the molds are self-locating through said ceiling-providing element affording an upstanding spacing flange or 15 stop for properly spacing the adjacently disposed molds.

Another object of the invention is to provide a simple mold structure in the nature of a framework over which may be wrapped and secured 20 metal lath or expanded metal.

In carrying out the invention, a succession of parallel disposed frames covered with a paper-lined metal lath or expanded metal are arranged to rest upon wood forms suitably supported, and 25 the portion of metal lath or expanded metal forming the bottom of such molds forms an integral ceiling element which may be extended beyond one of the sides of the mold and provided at its free end with an upstanding spacing flange 30 or stop adapted for engagement with the side of an adjacent mold.

The nature of the invention, however, will best be understood when described in connection with the accompanying drawing, in which:

35 Fig. 1 is a perspective sectional view, with floor slab partly broken away, illustrating the novel floor structure.

Fig. 2 is a fragmentary perspective view, with 40 portions broken away, of the novel mold utilized in the concrete structure shown in Fig. 1.

Fig. 3 is a fragmentary front elevation of a plurality of adjacent molds in spaced relationship.

Referring to the drawing, the usual wood forms, 45 as the planks 10 suitably sustained by the supports 11, are arranged between the floor beams, one of which is indicated at 12, the said wood forms being designed for the support of a plurality of molds 13. These are arranged to lie 50 parallel to one another, being self-locating as hereinafter set forth, and are provided with integral ceiling portions adapted to span the supporting wood forms 10.

Reference being had more particularly to Figs. 55 2 and 3, each mold is composed of a plurality of

longitudinal rods 15 and transverse rods 16 outlining in cross-section a polygon as a trapezoid. These rods are welded or otherwise secured to one another to form a final more or less rigid frame-work, and over the same is wrapped and attached, as by wires 17, a metal lath as the reticulated wire cloth 18 indicated; or, expanded metal may be utilized for the covering. This lath is also preferably lined on its inner side as by a paper sheet 19, and the lath is designed to 65 cover all four sides of the frame-work, the bottom 20 affording an integral ceiling element. Furthermore, the bottom portion or ceiling-forming element 20 thereof is continued beyond one of the sides, as the side 21, to afford an extension 22 which is further turned upwardly at its free end to provide a somewhat flexible spacing flange or 70 stop 23. It will be noted, also, that the bottom element 20 and extension 22 afford a ceiling on which plaster and the like may be applied in 75 the usual manner after the flooring has been completed and form 10 and supports 11 removed.

In applying the concrete to the flooring, the different molds are first located upon the wood forms 10 with bottom element 20 and extension 80 22 bridging the same, and are self-locating through the provision of the upstanding flange 23 which contacts with the side wall of an adjacent mold. Cap members 24 are then located over the respective ends of the molds to prevent concrete from filtering through any space 85 between the said ends and a beam or wall.

The concrete is then poured in the usual manner over the molds filling the spaces therebetween to provide the joists 25, reinforcing rods 90 26 having first been located in these spaces, and the pouring continued to provide the floor slab 27 of the desired thickness.

It will be observed that in the use of molds of the construction hereinbefore described, it is 95 not necessary to provide a separate ceiling lath and arrange for anchoring the lath to the molds as has been the practice heretofore. Moreover, the concrete forming the joists 25 will also serve to force the more or less flexible upstanding flange 100 23 of a mold against the corresponding wall of the adjacent mold to insure a tight joint therebetween.

The novel mold, also, is of very light construction and thereby reduces the dead load of the 105 floor construction with consequent reduction in cost of columns and footings in the erection of buildings thus constructed. It is, furthermore, cheaper in construction and installation than methods heretofore used, particularly due to the 110

absence of the usual independent ceiling element. It is possible, also, to assemble the frame-work of the molds either in a shop or in the field, and the same may also readily be made collapsible to 5 reduce freight charges and storage space.

We claim:

1. A combined ceiling and floor mold, comprising a plurality of longitudinal and transverse rods secured to one another as a succession of 10 integrally connected polygons, and metal lath secured over the rods, the bottom portion thereof being extended beyond one of the sides with the free end thereof turned upwardly to afford a spacing flange or stop for an adjacent mold.

15 2. A combined ceiling and floor mold, com-

prising a skeleton frame member embodying a succession of integrally connected polygons, and a hollow metal lath member wrapped thereover and secured thereto, with the bottom portion extended beyond one of the sides of the frame to afford an integral bottom ceiling element.

80

3. A combined ceiling and floor mold, comprising a plurality of longitudinal and transverse rods secured to one another as a succession of connected polygons, and metal lath secured over the rods, the bottom portion thereof being extended beyond one of the sides to afford an integral bottom ceiling element.
